(57) **CLAIM**

The ornamental design for a waste processing apparatus as shown and described.

DESCRIPTION

FIG. 1 is a front top perspective view of a waste processing apparatus showing our new design;

FIG. 2 is a rear bottom perspective view thereof;

FIG. 3 is a front view thereof;

FIG. 4 is a rear view thereof;

FIG. 5 is a left side view thereof;

FIG. 6 is a right side view thereof; and,

FIG. 7 is a top view thereof; and,

FIG. 8 is a bottom view thereof.

The broken lines immediately adjacent to the shaded areas define the bounds of the claimed design and form no part thereof. The broken lines depicting the remainder of the waste processing apparatus form no part of the claimed design.
